UNITED STATES PATENT OFFICE.

DIMMITT ROSS LOVEJOY, OF NIAGARA FALLS, NEW YORK, ASSIGNOR TO ATMOSPHERIC PRODUCTS COMPANY, OF NIAGARA FALLS, NEW YORK, A CORPORATION OF NEW YORK.

APPARATUS FOR SUBJECTING GASES TO HIGH-TENSION DISCHARGES.

No. 829,873.

Specification of Letters Patent.

Patented Aug. 28, 1906.

Application filed May 29, 1902. Serial No. 109,443.

To all whom it may concern:

Be it known that I, DIMMITT Ross LOVEJOY, a citizen of the United States of America, residing at Niagara Falls, in the county of Niagara and State of New York, have invented certain new and useful Improvements in Apparatus for Subjecting Gases to High-Tension Electrical Discharges, of which the following is a specification.

10 This invention relates to improvements in apparatus for subjecting gases to high-tension electrical discharges, and particularly to apparatus of the type disclosed in application of C. S. Bradley and D. R. Lovejoy, Serial No. 15 8,008, filed March 9, 1900. In such apparatus a series of electrodes is moved past another series of electrodes oppositely charged to a high tension, so as to successively form, elongate, and break a series of arcs between 20 such electrodes, inductances being included in circuit with the respective electrodes, so as to control the current which shall be allowed to flow through the respective arcs.

In the present invention the electrical energy may be supplied to the apparatus in the 25 form of unidirectional currents or in the form of alternating currents of any convenient frequency, and means are hereby set forth whereby the apparatus may be particularly 30 adapted for the utilization of alternating currents.

In the preceding application, Serial No. 8,008, the manner of using direct currents has been shown. In this application means 35 are shown whereby additional advantages and conveniences of operation are obtained in the following directions: First, that in the apparatus insulation for high voltages may be secured and permanently retained; second, 40 that the supply of fresh gases may most advantageously be introduced into the apparatus, and the converted gases in a like manner removed, and further incidental advantages of practical operation be obtained; 45 third, that the individual arcs may be substantially isolated from each other in order to prevent one arc from disassociating the nitrogen compounds formed by its neighbors; fourth, that the minimum supply of fresh 50 gases shall be required without sacrificing efficiency of conversion; fifth, that the required thinness of arcs may be more cheaply

obtained and their steadiness of operation be improved; sixth, that the apparatus may be particularly adapted to the use of alternating currents and that the said alternating currents may be made unidirectional (conveniently and without danger of short-circuiting in rectification apparatus) in order that the advantages of unidirectional currents may be secured and at the same time the facility with which high voltages may be secured through alternating currents and step-up transformers or direct generation of the same may be taken advantage of; seventh, that the gases may be supplied and acted upon at pressures higher than atmospheric pressure; eighth, that the energy residing in the gases by reason of their compressed state may be recovered in useful work after the gases have passed through the apparatus; ninth, that the gases may be separately charged to a high degree of electrostatic potential, lead individually to the apparatus and mixed therein in the presence of the arcs.

Referring to the accompanying drawings, which form a part of this specification, Figure 1 is a side-elevation of an apparatus embodying my invention, some of the inductances or choke-coils being, however, removed to show the parts beyond. Fig. 2 is a sectional elevation of the same, only one choke-coil being indicated. Fig. 3 is a horizontal sectional view of the same. Fig. 3^a is a similar fragmentary view showing a modification. Fig. 4 is a detail sectional view of the fixed and moving electrodes, showing the means of supporting the fixed electrode. Fig. 5 is a partly-sectioned side elevation of a horizontal form of the apparatus, the circuit connections being indicated in diagram and the form shown being particularly adapted for alternating currents. Fig. 5^a is a view of the transmitting-gear between the outlet-valve and the main shaft of the nitrifying-chamber. Fig. 6 is a diagrammatic view of the form of apparatus shown in Fig. 5. Fig. 7 is a sectional elevation of the apparatus as arranged for operation under pressure and for the recovery of the energy of the compressed gases. Fig. 8 is a similar view of the apparatus adapted for supplying the gases separately after they have been charged

electrostatically. Fig. 9 is a detail view of the insulating-coupling between the motor and the main shaft.

In the application Serial No. 8,008 and in the present invention the apparatus essentially comprises a cylinder or chamber 1, fixed electrodes 2, mounted around the inner periphery of the said chamber, a shaft 3, mounted to rotate within the said chamber, and movable electrodes 4, mounted mechanically upon said shaft and connected electrically thereto, an inlet or supply duct 5 for the supply of fresh gases, an outlet duct or ducts 6 for the removal of the nitrogen compounds formed, an exhaust-fan 7 or other means for causing flow of gases through the chamber, a source 8 of high-tension electrical currents, either unidirectional or alternating, a series of inductances or choke-coils 9, each having one terminal connected individually to one of the fixed electrodes 2 and having their remaining terminals grouped together and connected to one pole of the generators 8, the circuit being completed by connecting the shaft 3 by means of a conductor to the remaining pole of the generator 8.

In order that proper insulation for high voltages may be secured and permanently retained, I prefer to mount the shaft 3 in bearings 10 11, which are in turn mounted upon insulating-disks 12, attached to the ends of the chamber 1 and of sufficiently large diameter to secure a considerable distance between the shaft and the casing of the chamber, and so prevent surface leakage between shaft and chamber-walls. The lower bearing 10 is preferably made in the form of a cylinder, in which the lower end of the shaft fits as a plunger, thus securing a tight joint to prevent leakage of gas, and at the same time by forcing oil into the bottom of this cylinder by means of a pump 13 the whole shaft is lifted and carried on an oil-cushion, furnishing a practically frictionless step-bearing. In order to prevent leakage of gas at the bearing 11, this is constructed in the form of a stuffing-box, which may be packed in the ordinary way. To secure insulation of the opposite pole of the circuit, the fixed electrodes are preferably mounted in tubes or bushings 14, Fig. 4, of porcelain or other suitable material, which are passed through holes bored in the walls of the chamber 1, these holes being counterbored for a portion of their length, and a proper packing and stuffing-box 15 serve to firmly fix the tubes 14 in place and make a gas-tight joint. The electrodes may be accurately adjusted on loosening the stuffing-box. The electrodes proper, 2, are mounted in plugs 16, of brass or other suitable metal, which snugly fit the bore of the tube 14 and are also cemented therein. A wire 17 passes through the remaining distance and being electrically connected to the plug 16 serves to conduct the current to the

external source 8 of electrical energy. The tubes 14 are provided with thick walls and are made sufficiently long, so that their ends project inside and outside the wall of chamber 1 far enough to prevent any possibility of leakage from the conductor to the said walls of the chamber.

To insulate the shaft 3 from the motor 3^a, which drives it, an insulated coupling is provided, which is shown in detail in Fig. 9, in which the motor-shaft 18 and the main shaft 3 are respectively provided with flanges 19 20, firmly fastened thereto, to which are affixed, by means of screws or otherwise, the disks 21 22 of large diameter, these disks being of insulating material. Between the disks 21 22 is another disk 23, of insulating material and slightly smaller in diameter. Lastly, a band 24 is tightly fitted to the peripheries of the disks and serves to transmit the power from disk 21 to disk 22, and thus drive the shaft 3. Disks 21 and 22 are of large diameter to prevent leakage around the outside surfaces, and disk 23 is sufficiently thick to prevent leakage or breakdown through its mass. As a further and additional precaution I prefer to mount the motor 3^a on insulating legs or standards 25 and the whole chamber on an insulating-frame 26.

In order that the fresh gases may be most advantageously supplied and the nitrogen compounds most promptly and effectively removed, I prefer to provide the supply pipe or duct 5 with two branches, one connecting with each end of the chamber 1 and terminating near the bearings of the shaft 3 in such a manner as to direct the incoming gases, which have been previously cooled or chilled by means of a refrigerating apparatus, (not shown, but of an usual or preferred form,) against the ends of the shaft, and so help to keep it and its bearings cool.

For the outlet-ducts one or more extensions 27 are formed in the walls of the chamber (in this case six are shown) and communicating with outlet-pipes 6. These extensions have their open sides toward the interior of the chamber covered by flaps or sheets 28, these sheets being tightly fastened down along one edge and at the ends, and the remaining edge is partially raised, pointing in a circumferential direction contrary to the direction of rotation of the shaft 3 and electrodes 4, so that a narrow channel or opening 29 is left, establishing communication between the interior of the chamber 1 and the extended space 27, which, with its connecting-pipes 6, thus becomes an outlet-duct for the nitrogen compounds formed by the arcs within the chamber. The openings or slits 29, formed by the plates or flaps 28, are thus favorably situated to have the nitrous compounds swept directly into them by the rotation of the whole mass of gas within the chamber, and they are preferably situated just be-

yond the arcs in the direction of rotation, so that the nitrogen compounds formed by one row of arcs is instantly carried forward and into the next outlet in the direction of rotation. To this end the stationary electrodes 2 are set in the periphery of the chamber in a direction contrary to the direction of rotation at a distance from the slits 29 somewhat greater than the maximum length of the arc 5 which is drawn out from the stationary electrode 2 by the moving electrode 4. A further advantage of so arranging the outlet-slits 29 is that the outside edge of the rotating mass of gas is continually shaved off, so to speak, and fresh gases being supplied at each end of the chamber near the shaft a well-defined direction is given to the flow of gases within the chamber, the unconverted gases 10 passing spirally outward and after passing through the arcs being promptly removed at the outer surface of the rotating mass. The mass of gas within the chamber does not of course rotate at the same speed as the shaft and electrodes, but at a less speed in the 15 same direction, so that the effect is substantially as described, thus securing the prompt removal of the nitrogen compounds and preventing their being disassociated by coming in contact with other arcs in the chamber. 20 As a further means of preventing this I prefer to isolate each arc from its neighbor by means of barriers 30, of non-combustible and preferably of non-conducting material, fastened to the interior surface of the chamber 1 and projecting inwardly for some distance beyond the ends of the fixed electrodes 2. The shape of these barriers is shown by the 25 full lines in Fig. 3; but any other suitable form may be used—for instance, a continuous 30 ring 31, as shown in Fig. 3^a.

In order to have the nitrogen compounds drawn out of the chamber as dense (free from unconverted gases) as possible, it is desirable to use as slow a draft of gases through 45 the chamber as is consistent with the substantially immediate removal of the compounds formed. I have found that a slower draft may be used without sacrifice of efficiency if the said draft be made not continuous, but intermittent, and the impulses of flow 50 so timed as to commence just after the arcs are struck and to cease just after the arcs are extinguished. Thus the gases are drawn out only when the nitrogen compounds are being 55 formed and not at any other time. In order to effect this, I prefer to include in the outlet 6, Fig. 5, a valve 32, which is actuated by means of a perforated belt or other positive connection 33 with the shaft 3, so that this 60 valve is opened and closed in synchronism with the rotation of the said shaft, the arrangement being so adjusted that the valve is open during the time the arcs are in operation and closed during the remainder of the 65 time. In the chamber shown in Fig. 5, in

which there are but two rows of electrodes, the valve would be opened and closed twice during each revolution of the shaft 3, whereas in the chamber shown in Figs. 1, 2, and 3, which has six rows of electrodes, the valve 70 would be actuated a corresponding number of times in each revolution.

In Fig. 5^a the details of the transmitting-gear from the shaft 3 to valve 32 are shown, the belt 33 being perforated and running on 75 sprocket-wheels 34 and 35 on shaft 3 and the spindle 36 of valve 32, respectively. An adjustable screw-and-slot connection 37 between sprocket-wheel 35 and spindle 36 enables the time of operation of the valve 32 to 80 be adjusted. In order that arcs of the required thinness may be readily obtained and their steadiness of operation secured, I provide the moving electrodes with fine tips, which may be of round, flat, or other cross- 85 section and are preferably of platinum wire, and make the fixed electrodes of somewhat thicker wire, bent into proper shape, as in Fig. 4, and fastened to studs or plugs of comparatively heavy construction. The moving electrode 4 has therefore the body part or shaft 4^a and its fine tip 4^b, while, as already stated, 2 is the tip of the stationary electrode fastened into the plug or stud 16, which is in turn supported in the insulating bushing or 90 tube 14.

The advantage of using fine-pointed movable electrodes and fixed electrodes of small size lies in the fact that at a given speed of rotation the interval in which the electrodes 100 are opposite each other is greatly shortened and the time during which the current in the arc is increasing is correspondingly reduced. This enables inductances of much smaller value and corresponding cheapness of construction to be employed, whereas if the electrodes were of large size this time interval would be much longer and the choking-coils 105 must be of greater self-induction in order to limit the arc-current to the same low value as before with a given electromotive force of the supply-circuit. Moreover, I have found that if the fixed electrodes be properly proportioned as to size, so that they will be raised appreciably in temperatures by the arcs, 110 the said arcs burn much more steadily and efficiently. The movable electrode-tips may be of much smaller size than the fixed electrodes, because their high speed and consequent good ventilation prevents their temperature from rising to as high a degree as the larger fixed electrodes. In short, I make the fixed and movable electrodes as small as possible consistent with temperature and mechanical limitations. One or other of the 115 electrodes is bent vertically to provide for slight differences in vertical adjustment of the other electrode. Preferably the fixed electrode, it not being subject to centrifugal action, is, as shown, so formed. 120 125 130

In order to adapt the apparatus particularly to the use of alternating currents, the movable electrodes are rotated at such a speed (synchronous with the periodicity of the alternations of the generator 8) that they approach within arcing distance of the stationary electrodes once during each half-period of the alternating current. This is preferably effected by driving the shaft to which the movable electrodes are fixed by means of a synchronous motor which is driven by current from the same generator that supplies current to the arcs or from any other source in synchronism therewith. When operated in this manner, the principal feature consists in the timing or isochronism of the making and extinction of the arcs with the alternations of the generator, and to this end I prefer to drive the shaft 3 by means of a synchronous motor 3^a, which is energized from the generator 8 through the intermediary of a step-transformer 38.

It is desirable to provide means for adjusting the angular position of the electrodes 4 with reference to the phase of the alternating electromotive force supplied to the electrodes 2 4, so as to bring the time of formation and disruption of the arc in any desired phase of the alternation. For example, the arcs may be started or struck at the instant when the electromotive force is at its maximum value and drawn out as the electromotive force falls to zero, or the arcs may be struck earlier in the wave, so as to permit them to be drawn out to a greater extent, thus providing a ready means of regulating the length, volume, and efficiency of the arcs. To enable such adjustment to be made while the apparatus is in operation, I prefer to mount the stator 39 of the synchronous motor 3^a on a circular way or guide 40, concentric with its shaft 18, and to provide a worm and wheel 41 or other suitable device, so that the said stator may be rotated in either direction through the angle through which adjustment may be required.

Inasmuch as I have discovered that the direction of the current in the arc—*i.e.*, whether from moving electrode to fixed electrode, or vice versa—has considerable effect on its efficiency and manageability, I provide means for rectifying the alternating current in such a manner as to cause it to always flow in the same direction with respect to the electrodes. This is accomplished by a rectifying-commutator 42, mounted on the shaft 3, Fig. 6, and consisting of two insulating-disks 43 43^a, one of which has on its periphery a continuous conducting-ring 44 and the other a ring split 60 into two segments 45 46, thoroughly insulated from each other and having long insulating-gaps 47 between them. Two brushes 48 bear upon these segments and are connected to the generator 8. One segment 45 65 is connected permanently to the shaft and

the other, 46, to the ring mounted on the other disk 43. A brush 49 bearing on this ring serves to conduct the rectified current to the common terminal of the inductances 9.

The angular position of the segments 45 46 is so adjusted with reference to the movable electrodes 4 that the brushes bearing thereon come into electrical contact with the said segments just before the electrodes 4 come within striking or arcing distance of the electrodes 2 and remain in contact until after the arcs have been drawn out and extinguished. The effect of this disposition is to cause the brushes to cross the insulating-gaps when no current is flowing, and there is consequently no flashing at the brushes and no danger of short-circuiting across the gaps between the segments. This device enables both the advantages of direct and alternating currents to be utilized, as before stated. 85

Inasmuch as I have found it to be of advantage to operate the arcs in gases at pressures higher than atmospheric pressure, I provide means whereby the chamber 1 may be made to withstand high pressures and at the same time make possible the recovery and utilization of the energy residing in the gases by reason of their compressed state. To this end instead of causing the flow of gases through the chamber by means of an exhaust-fan connected to the outlet-duct I prefer to make the chamber with heavy walls and of a material and shape adapted to withstand high pressures, provide gas-tight bearings for the shaft 3, and force the fresh gases into the chamber by means of a compressor 50 up to the required degree of pressure, and regulate the velocity of flow of the gases through the chamber by means of a valve, such as 32, or a separate hand-regulated valve 51, (see Fig. 7,) in the outlet-duct or (where it is desired to recover the energy of the compressed gases) by means of the load on an engine 52, Fig. 7, through which the gases are expanded down to normal pressure, the gases being then carried to collection apparatus (not shown) for the removal of the nitrogen compounds. 110

In order that the two gases may individually be given an electrostatic charge before being brought into the presence of the arcs, the chamber 1 is provided with two distinct sets of inlet-ducts which are preferably of insulating material, and included in the path of each gas is an electrifying-chamber 53 54, 120 these containing electrodes 55 56, which are adapted to electrostatically charge the molecules of the gases in contact therewith and which are connected to the source of high unidirectional potential 57. The two gases 125 after being electrified are mixed in the chamber 1 in the presence of the arcs or just previously to coming into the presence of said arcs. This part of the apparatus is shown in Fig. 8, so much of the apparatus as is necessary to 130

an understanding of the electrifying devices being shown in diagram.

The process here described is not claimed herein, but in a separate application, Serial 5 No. 112,894, filed June 24, 1902.

As an illustration of the use of the device may be cited the formation of nitrous compounds from air. With a chamber having one hundred and eighty fixed electrodes and 10 three hundred and sixty revolving electrodes—i. e., six rows of electrodes, thirty in each row, and thirty sets of revolving wires, twelve in a set, the length of the revolving wires from tip to tip of the electrodes being 15 thirty-six inches, and the inside height of the chamber about five feet six inches, the shaft carrying the electrodes being rotated at a speed of four hundred revolutions per minute and with air passing through the chamber at 20 the rate of about sixteen cubic feet per minute, with a voltage of about five thousand six hundred and a current of three amperes—there is obtained a resulting yield of nitrous fumes equivalent to fourteen and one-half 25 grams HNO_3 per minute. The compounds obtained consist of N_2O_3 , N_2O_4 , and a trace of NO , which, taken together, are equivalent to fourteen and one-half grams HNO_3 , as above stated. It is to be understood that the 30 above is given merely as an illustrative instance of the use of the apparatus and that with other gases and variations in their treatment a variety of products may be obtained.

35 Having thus described my invention, what I claim as new therein, and desire to secure by Letters Patent, is—

1. In an apparatus for subjecting gases to high-tension electrical discharges, the combination of a chamber for inclosing the gases, 40 means comprising electrodes to rapidly and successively form, elongate and extinguish a plurality of electric arcs within the chamber, said electrodes being of minimum size to insure the formation of arcs of minimum volume.

2. In an apparatus for subjecting gases to high-tension electric discharges, a chamber for inclosing the gases, sets of relatively movable electrodes within said chamber, arranged to pass within arcing distance of each other, said electrodes being formed of fine wire and each pair of electrodes arranged in the same plane of movement, means to permit of adjustment of said pairs of electrodes relative to their plane of movement while preserving their arcing relation, and a source of high-tension current connected with said electrodes, substantially as described.

60 3. In an apparatus for subjecting gases to high-tension electric discharges, a chamber for inclosing the gases, sets of relatively movable electrodes within said chamber, said electrodes being formed of fine wire, one of 65 each pair of said electrodes bent transversely

to the plane of movement, and a source of high-tension current connected to said electrodes.

4. In an apparatus for subjecting gases to high-tension electric discharges, sets of relatively movable electrodes connected to a source of high-tension current and arranged to pass within arcing distance of each other, 70 a chamber inclosing the gases and electrodes, means for independently adjusting the gap between the electrodes of each pair.

5. In an apparatus for subjecting gases to high-tension electric discharges, sets of relatively movable electrodes connected to a source of high-tension current and arranged to pass within arcing distance of each other, 80 a chamber inclosing the gases and electrodes, the electrodes of one polarity being adjustably mounted in the wall of said chamber.

6. In an apparatus for subjecting gases to 85 high-tension electrical discharges, a chamber for inclosing the gases, a source of high-tension current, a plurality of sets of electrodes within the chamber and connected in parallel with said source of current, means to 90 move some of said sets of electrodes relatively to the others to successively form, elongate and extinguish arcs between them, and means for insuring a minimum volume and minimum current for each of said arcs, 95 said means comprising an inductance in each of said parallel electrode-circuits and said electrodes constructed of fine wire, substantially as described.

7. In an apparatus for subjecting gases to 100 high-tension electric discharges, sets of relatively movable electrodes arranged to pass within arcing distance of each other, a source of high-tension current connected to said electrodes, a chamber inclosing said electrodes and gases, and outlets for the products arranged in close proximity to the arcing-points.

8. In an apparatus for subjecting gases to 105 high-tension electric discharges, a chamber for receiving the gases, sets of relatively movable electrodes within said chamber adjacent the walls thereof and arranged to pass within arcing distance of each other, a source of high-tension current connected to said electrodes, means to conduct the gases to the central portion of said chamber, a series of outlets in the walls of said chamber adjacent the arcing-points and deflectors for said outlets to deflect the products formed by the 110 arcs into the outlets.

9. In an apparatus for subjecting gases to 115 high-tension discharges, the combination of a containing-chamber, electrodes mounted in the walls of said chamber, a shaft rotatably mounted in said chamber, supports carried by said shaft, and electrodes at the ends of said supports, means to cause arc-discharges between the said electrodes and near the wall of the chamber, gas-inlets for the 120

chamber said inlets conducting and discharging gases at the interior of the chamber and against said shaft, and outlets for the combined gases in close proximity to the 5 electrodes.

10. In an apparatus for subjecting gases to high-tension electric discharges, a chamber for receiving the gases, sets of relatively movable electrodes within said chamber adjacent the walls thereof and arranged to pass within arcing distance of each other, a source of high-tension current connected to said electrodes, a rotary shaft having insulated bearings in the walls of said chamber and 15 carrying the electrodes of one polarity, means to conduct the gases into said chamber adjacent the bearings of said shaft, outlets for the products in the walls of the chamber adjacent to the arcing-points, deflectors 20 for said outlets directed contrary to the direction of rotation of said shaft, as and for the purpose described.

11. In an apparatus for subjecting gases to high-tension electric discharges, a chamber 25 for receiving the gases, sets of relatively movable electrodes within said chamber adjacent the walls thereof and arranged to pass within arcing distance of each other, a source of high-tension current connected to said 30 electrodes, means to conduct the gases to the central portion of said chamber, means to give said gases an outward spiral motion within said chamber, outlets in the walls of the chamber in proximity to the arcing-points 35 and deflectors for said outlets directed contrary to the motion of the gases.

12. In an apparatus for subjecting gases to high-tension electric discharges, a chamber for receiving the gases, sets of relatively 40 movable electrodes within said chamber and arranged to pass within arcing distance of each other, a source of high-tension current connected to said electrodes, means to conduct gases into said chamber, a series of outlets in proximity to the arcing-points and 45 means to isolate the arcing-points, for the purpose described.

13. In an apparatus for subjecting gases to high-tension electric discharges, a chamber 50 for receiving the gases, sets of relatively movable electrodes within said chamber and arranged to pass within arcing distance of each other, to form and extinguish arcs, a source of high-tension current connected to 55 said electrodes, means to cause an intermittent flow of gases into said chamber, impulses of the flow being timed to commence just after the arcs are struck and to cease just after the arcs are extinguished.

60 14. In apparatus for subjecting gases to high-tension discharges, in combination with a containing-chamber, relatively fixed and movable electrodes therein, a circuit including said electrodes, a source of current of 65 high potential, means for moving said mov-

able electrodes causing the formation and extinction of arcs between said fixed and movable electrodes, inlet and outlet passages for gas, and means for causing an intermittent flow of gas synchronous with the formation 70 and extinction of the arcs.

15. In apparatus for subjecting gases to high-tension discharges, in combination with a containing-chamber, relatively fixed and movable electrodes therein, a circuit including said electrodes, a source of current of high potential, means for moving said movable electrodes causing the formation and extinction of arcs between said fixed and movable electrodes, inlet and outlet passages for gas, 80 and a valve or valves in the gas-ducts having means for intermittently opening and closing it in synchronism with the formation and extinction of the arcs.

16. In apparatus for subjecting gases to 85 high-tension discharges, in combination with a containing-chamber, relatively fixed and movable electrodes therein, a circuit including said electrodes, a source of current of high potential, means for moving said movable 90 electrodes causing the formation and extinction of arcs between said fixed and movable electrodes, inlet and outlet passages for gas, and a valve or valves in the outlet duct or ducts having means adapted to intermittently open and close it in synchronism with the formation and extinction of the arcs. 95

17. In apparatus for subjecting gases to high-tension discharges, in combination with a containing-chamber and relatively fixed 100 and movable electrodes therein, an electric circuit including said electrodes, a generator of alternating currents connected to said circuit, and means for causing motion of said movable electrodes in synchronism with the 105 alternations of said current.

18. In apparatus for subjecting gases to high-tension discharges, in combination with a containing-chamber, relatively fixed and movable electrodes therein, an electric circuit including said electrodes, and a generator of alternating current, and means for adjusting the angular position of the moving electrodes relative to the fixed electrodes and relative to the phase of the alternating current. 115

19. In apparatus for subjecting gases to high-tension discharges, in combination with a containing-chamber, relatively fixed and movable electrodes therein, an electric circuit including said electrodes, and a generator of alternating current, driving means for said movable electrodes, and means for rotary adjustment of said driving means whereby the angular position of the moving 120 electrodes relative to the fixed electrodes and relative to the phase of the alternating current may be adjusted. 125

20. In apparatus for subjecting gases to high-tension discharges, in combination with 130

a containing-chamber, relatively fixed and movable electrodes therein, an electric circuit including said electrodes, and a generator of alternating current, and a rectifier, 5 and means for driving the same in synchronism with the movable electrodes.

21. In apparatus for subjecting gases to high-tension discharges, in combination with a containing-chamber, relatively fixed and 10 movable electrodes therein, an electric circuit including said electrodes, and a generator of alternating current, a rectifier so adjusted with respect to the fixed and movable electrodes as to reverse the connections of the 15 electrodes with respect to the supply-circuit during the time when the arcs are extinguished.

22. In an apparatus for subjecting gases to high-tension electric discharges, a chamber 20 for receiving the gases, sets of fixed and movable electrodes within said chamber and arranged to pass within arcing distance of each other, an alternating-current generator connected to said electrodes, driving mechanism 25 for the movable electrodes and means to control the driving mechanism to cause the formation of the arcs during each half-period of alternating current.

23. In an apparatus for subjecting gases to 30 high-tension electric discharges, a chamber for receiving the gases, sets of fixed and movable electrodes within said chamber and arranged to pass within arcing distance of each other, an alternating-current generator connected to said electrodes, a synchronous motor 35 connected with the generator and having driving connection with the movable electrodes, and means to adjust the making and extinction of the arcs relatively to the alternation and phase of the alternating current.

24. In an apparatus for subjecting gases to high-tension electric discharges, a chamber for receiving the gases, sets of fixed and movable electrodes within said chamber and arranged to pass within arcing distance of each other, an alternating-current generator connected to said electrodes, a synchronous motor 45 connected with the generator and having driving connection with the movable electrodes, said motor mounted on the chamber and insulated therefrom, an insulating-coupling between said motor and the movable electrodes, and means to adjust said motor and movable electrodes radially for the purpose described.

25. In an apparatus for subjecting gases to high-tension electric discharges, a plurality of electrodes and means successively to form and extinguish arcs between the same, means 60 to conduct the gases to said electrodes, a source of alternating current connected to said electrodes, a rectifier in the alternating-current circuit, said rectifier having means to cause the reversals of current during the extinctions of the arcs whereby the same po-

tential relation between the electrodes is maintained.

26. In an apparatus for subjecting gases to high-tension electric discharges, a chamber for receiving the gases, sets of fixed and movable electrodes within said chamber and arranged to pass within arcing distance of each other, an alternating-current generator connected to said electrodes, a synchronous motor connected with the generator and having driving connection with the movable electrodes, means to adjust the making and extinction of the arcs relatively to the alternation and phase of the alternating current, a rectifier in the alternating-current circuit 75 and having its commutator moving with the movable electrodes and arranged to cause reversals of current during extinctions of the arcs.

27. In an apparatus for subjecting gases to 80 high-tension discharges, the combination of a containing-chamber, a plurality of movable and fixed electrodes within the chamber adjacent the walls thereof, and means to rapidly and successively form, elongate and extinguish arcs between said electrodes, means for introducing gases to the central portion of said chamber at a pressure greater than atmospheric pressure, a series of gas-outlets in the walls of the chamber adjacent the 85 fixed electrodes, and gas-ducts leading from said outlets.

28. In an apparatus for subjecting gases to 90 high-tension discharges, the combination of a containing-chamber, electrodes adjustably mounted in the walls thereof, a series of movable electrodes mounted within the chamber and arranged to pass within arcing distance of the fixed electrodes, a source of high-tension current connected to the electrodes, gas-inlets leading to and discharging near the 95 central portion of said chamber, a gas-outlet in the walls of said chamber adjacent each fixed electrode, ducts leading from said outlets, and means to supply gases to the gas-inlets at a pressure higher than atmospheric pressure.

29. In an apparatus for subjecting gases to 100 high-tension discharges, the combination of a containing-chamber, a series of electrodes 105 mounted in the walls thereof, and a series of movably-mounted electrodes within the chamber, a source of high-tension current connected to the electrodes, and means to cause the movable electrodes to pass within 110 arcing distance of the fixed electrodes, means to supply gases to the central portion of said chamber at a pressure higher than atmospheric pressure, a gas-outlet in the walls of the chamber adjacent each fixed electrode 115 and beyond the same in the direction of movement of the movable electrodes, a deflector for said outlet arranged to deflect gases from the chamber through the outlet 120 and ducts connected with said outlet.

30. In apparatus for subjecting gases to high-tension discharges, the combination of means for separately charging the molecules of said gases electrostatically, a chamber, means for maintaining in said chamber electric arcs, means for leading said separately-charged gases into said chamber and for allowing them to commingle in the presence of said arcs or just before coming into said presence.
31. In an apparatus for subjecting gases to high-tension discharges, the combination of a chamber for inclosing the gases, a series of electrodes within the chamber and mounted in walls thereof, a series of movable electrodes mounted within the chamber and arranged to pass within arcing distance of the fixed electrodes, a source of high-tension current connected to the electrodes, and means to isolate the arc formed between each pair of electrodes from the arc formed between adjacent pairs of electrodes.
32. In an apparatus for subjecting gases to high-tension electric discharges, the combination of a chamber for inclosing the gases, gas-inlets for conducting gases into said chamber near the central portion thereof, relatively fixed and movable electrodes in said chamber, means to rapidly and successively form, elongate and extinguish arcs between said electrodes, means to isolate the gas immediately affected by the arc between one pair of electrodes from the effect of adjacent arcs, a gas-outlet arranged adjacent each arcing-point to immediately discharge the gas affected by each arc from the chamber. 25 30 35
